[57] CLAIM

The ornamental design for an automotive cup holder, as shown and described.

DESCRIPTION

FIG. 1 is a perspective view of an automotive cup holder showing my new design in use;

FIG. 2 is a top plan view;

FIG. 3 is a bottom plan view; and,

FIG. 4 is a side elevational view.

The broken line showing of a cup and vehicle interior in FIG. 1 is for illustrative purposes only and forms no part of the claimed design.

FIG. 1

FIG. 2

FIG. 3

FIG. 4
